UNITED STATES PATENT OFFICE.

GEORGE RICHARD COLIN CAMPBELL, DECEASED, LATE OF SLOUGH, ENGLAND, BY
EDWARD FITZHARDINGE CAMPBELL, ADMINISTRATOR, OF MOY, IRELAND, AND
GEOFFREY THOMAS BENNETT, OF SLOUGH, ENGLAND.

MAGNETIC COMPASS.

1,341,296.

Specification of Letters Patent.

Patented May 25, 1920.

Application filed July 1, 1919. Serial No. 308,061.

To all whom it may concern:

Be it known that GEORGE RICHARD COLIN CAMPBELL, late of Slough, in the county of Bucks, England, a subject of the King of 5 Great Britain, jointly with GEOFFREY THOMAS BENNETT, a subject of the King of Great Britain, residing at The Admiralty Compass Observatory, Slough, in the county of Bucks, England, have invented a new 10 and useful Improved Magnetic Compass, of which the following is a specification.

In all liquid magnetic compasses so far constructed the needle or needle system will, on being deflected from its position of rest, 15 execute a series of diminishing oscillations about that position before settling. The oscillatory motion of all such compasses is, for small amplitudes, of the type known as damped harmonic. In this type of motion 20 the magnetic restoring couple is proportioned to the angular displacement from the equilibrium position, and the resistance due to the damping of the liquid is, for slow movements, proportional to the angular velocity. According as this damping resistance is below or above a certain amount, for 25 any given angular velocity, the resulting motion is one of two distinct types. If the damping is below the critical value the needles will oscillate isochronously on each side of the equilibrium position with continually diminishing amplitude. But if the damping is above the critical value the needles will return direct to the equilibrium 30 position without oscillation. Such a motion is said to be aperiodic; and conditions adequate to secure this type of motion are produced in the compass forming the subject of this invention.

40 It is to be understood that if the liquid itself be in circulation, as from previous rotation of the bowl, or from the stirring action of the filaments during a wide swing, the needles may move past the meridian and 45 return thereto; but that this motion, though temporarily oscillatory, is definitely aperiodic.

The amount of damping requisite to produce aperiodic motion in stationary liquid 50 is obtained according to the invention by attaching to the needles a radial filament or filaments made of glass, wire, or other suitable material, in contradistinction from ribs

or wings attached to the needle system and moving broadside through the liquid as previously proposed and employed in such compasses. In all cases the aim is to produce a high damping resistance as the filament or filaments move through the fluid inside the bowl, while at the same time the smallest 55 possible addition is made to the moment of inertia of the revolving mass of the needle system.

An aperiodic magnetic compass suitable for an aeroplane is illustrated by way of 60 example in the accompanying drawing, in which:—

Figure 1 is a sectional side elevation of the compass, and

Fig. 2 is a perspective view drawn to a 70 larger scale of the needle system detached.

a indicates the bowl of the compass and *b* the stand or support therefor. *c* indicates a skeleton hemispherical dome which is constructed of ribs carrying at the summit 75 the pivot *d* and girdled at the lower end by the ring *e*. To the ring *e* are attached two carriers *f* each of which holds three bar magnets *g*.

h, *h* are the damping filaments, here eight 80 in number, which are attached to the dome *c* and project in the direction of the cardinal and quadrantal points. Letters N. E. S. W., abbreviations of the names of the cardinal points, are attached to the filaments which 85 point in those directions respectively.

Claims—

1. A liquid magnetic compass armed with one or more filaments included in the needle system and adjusted so as to produce by 90 their motion through the liquid a damping effect adequate to convert the common periodic oscillatory movement of the magnetic compass into a movement of the kind usually termed "dead-beat" and herein referred to 95 as aperiodic.

2. In a liquid magnetic compass, the combination with a needle system, of relatively long filaments included in the needle system and extending radially from the compass 100 axis to produce by their motion through the liquid a damping effect adequate to convert the common periodic oscillatory movement of the compass into an aperiodic movement.

3. In a liquid magnetic compass, the com-

bination with a pivot port, of a ring associated therewith and provided with holders, a plurality of bar magnets carried by each holder, and a plurality of relatively long 5 filaments attached to said ring and extending radially from the compass axis to produce by their motion through the liquid a

damping effect adequate to convert the common periodic oscillatory movement of the compass into an aperiodic movement.

EDWARD FITZHARDINGE CAMPBELL,
Administrator of George Richard Colin Campbell, deceased.

GEOFFREY THOMAS BENNETT.
